ELECTRICAL RADIATION APPARATUS

Ulrich Schönfeld, Berlin-Pankow, Germany, assignor to Steatit-Magnesia Aktiengesellschaft, Berlin-Pankow, Germany, a Corporation of Germany

Application March 25, 1931, Serial No. 525,257,
and in Germany March 31, 1930

3 Claims. (Cl. 219—19)

5 My invention relates to improvements in electrical radiation apparatus, and more particularly in radiation apparatus in which a resistance wire or wires are supported on an insulating plate of refractory material, and which are used for heating or cooking purposes. The object of the improvements is to provide an apparatus of this type in which the position of the resistance wire or wires relatively to each other and to the refractory base is not affected by heating the wires. With this object in view my invention consists in constructing the heating coil and the base so that the coil is clamped on the base by spring action. In carrying out the invention I construct the windings of the heating wire or coil in crescent form, the crescent-shaped windings embracing a rib or ribs projecting from the insulating base, and being held thereon by spring action.

20 For the purpose of explaining the invention several examples embodying the same have been shown in the accompanying drawing, in which the same letters of reference have been used in all the views to indicate corresponding parts. In said drawing,

25 Fig. 1 is an elevation showing the radiation apparatus,

Fig. 2 is a top plan view of Fig. 1,

30 Fig. 3 is a perspective view on an enlarged scale showing the resistance coil separate from the base,

Fig. 4 is an end elevation of the said coil,

35 Fig. 5 is a perspective view on an enlarged scale showing one of the coils illustrated in Figs. 1 to 4 and a portion of the base supporting the same,

Fig. 6 is a plan view showing a modification of the radiation apparatus, the heating coil being supported on a spiral rib,

40 Fig. 7 is a detail sectional elevation showing a modification in which the heating coil has the form shown in Figs. 1 to 5, which coil is supported on a pair of ribs projecting from the base,

Fig. 8 is a similar sectional elevation showing 45 another modification in which the rib supporting the heating coil is X-shaped in cross-section.

In the construction shown in Figs. 1 and 2 the radiation apparatus comprises a base plate *a* of ceramic material such as steatite, porcelain or 50 the like, and four rectilinear bars *b* disposed parallel to each other and, preferably, made integral with the base plate *a*. Thus the bars are in the form of ribs projecting from the base plate, and they are reduced in thickness at their median 55 parts. The ribs *b* provide supports for heating

coils *c* which are made for example from a chromium nickel alloy.

As appears from Figs. 3 and 4, which show the heating coil in detail, the said coil consists of a helically wound wire. But the windings of the 60 coil are not circular, as is usual, but they are bent into crescent shape, as is best shown in Fig. 4, each winding comprising two concentric portions *c*₁ and *c*₂ and rounded connecting portions *c*₂, *c*₂, the said winding being in shape similar 65 to an open ring. As appears from Fig. 3, each winding comprises an outer arc-shaped section *c*₁ which extends in helical form from one side of the rib *b* to the opposite side thereof, where it is connected by the curved portion *c*₂ with the inner arc *c*₃ which extends in helical form from the said side of the rib to the opposite side, and which at the said opposite side merges by a small curved portion *c*₂ into the next large arc *c*₁, etc. 70 The windings *c*₁ and *c*₃ respectively are disposed 75 close to each other, so that effective heating is insured. I wish it to be understood that in the drawing the distance between adjacent coils is comparatively large merely for convenience in illustration, and that practically the said distance 80 is considerably smaller.

The winding *c* embraces the enlarged head *b*₂ of the rib *b*, the arc-shaped portions *c*₂ engaging the lateral recesses *b*₁ of the rib. By elasticity 85 of the sections *c*₁, *c*₃ of the windings the curved portions *c*₂ are pressed into the recesses *b*₁, so that the adjacent windings cannot be shifted longitudinally of the coil and the rib *b* when the wire is heated and expanded. Therefore the adjacent windings remain out of contact with each 90 other, so that short circuits are avoided. Further, only a very small portion of each winding is covered by the head *b*₂ of the rib *b*, so that the heating capacity is high.

The coil *c* shown in Fig. 3 may be manufactured by first manufacturing a circular or oval coil, and thereafter bending the corresponding portions of the winding inwardly and into the form of a C, such bending being preferably effected while the wire is at red heat and pliable. 100 In a modification of the method the windings are bent into C-form while the coil is being wound.

The crescent-shaped coil *c* is placed on the base *a* by passing the same on the rib *b* from 105 one end thereof and longitudinally of the rib, so that the curved portions *c*₂ engage in the recesses *b*₁. But if the elasticity of the coil is sufficient it may be placed on the rib *b*₂ from the 110 top side thereof downwardly.

To the plate *a* clamping screws *d* are fixed to which the free ends of the coils *c* are secured, all the coils mounted on the ribs being connected in series. To the outer terminals *d* leading-in wires 5 *m* are secured, as is shown in Fig. 2.

Instead of providing the base *a* with individual ribs disposed parallel to one another, I may provide the same with ribs which cross one another to provide a grate. Further, the ribs may 10 be provided with longitudinal recesses or grooves.

In Fig. 6 I have shown a modification in which a circular base *e* is provided with a single spiral rib *f*, which rib is similar in cross-section to the ribs *b* shown in Figs. 1 to 5. On the said spiral 15 rib *f* a heating coil *c* is mounted which has the form of a crescent, a C, or an open ring, as has been described with reference to Figs. 1 to 5.

In lieu of the rib *b* formed on the base *a* and having the heating coil *c* clamped thereon I may 20 provide a pair of spaced ribs *g* having beads *g*₁ at their outer top ends, as is shown in Fig. 7, the said beads providing recesses *g*₂ which are engaged by the curved portions *c*₂ of the heating coils *c*.

25 In Fig. 8 I have shown a modification in which the rib carrying the heating coil is X-shaped in cross-section, as is shown at *h*. The curved portions *c*₂ of the heating coil *c* engage in the recesses *h*₁ provided by the arms of the rib *h*.

30 I claim:

1. A radiation apparatus, comprising a base

of insulating material in the form of a bar having longitudinal recesses at its sides, and a crescent-shaped heating coil engaging said recesses and held on said base by spring action, each turn of the heating coil comprising an inner and outer portion defining the outline of a crescent and connected to each other, the portions of each turn lying in substantially the same radial plane. 80

2. A radiation apparatus, comprising a base 85 of insulating material and in the form of a bar having longitudinal recesses at its sides, and a crescent-shaped heating coil engaging said recesses and held on said base by spring action, said heating coil being composed of helically disposed windings each comprising an outer arc and an inner concentric arc, defining the outline of a crescent and connected together in reverse magnetic effect, the portions of each turn lying in substantially the same radial plane. 90

3. A radiation apparatus, comprising a base 95 of insulating material and in the form of a bar having longitudinal recesses at its sides, and a crescent-shaped heating coil comprised of inner and outer superposed turns, the inner turns engaging said recesses and holding on said base by the spring action at their ends, said turns comprising substantially C-shaped windings arranged in zigzag. 100
